UNITED STATES PATENT OFFICE.

HARRY SHOEMAKER, OF PHILADELPHIA, PENNSYLVANIA, ASSIGNOR TO
MARIE V. GEHRING AND THE CONSOLIDATED WIRELESS TELEGRAPH
AND TELEPHONE COMPANY, OF PHILADELPHIA, PENNSYLVANIA.

WIRELESS SIGNALING SYSTEM.

SPECIFICATION forming part of Letters Patent No. 717,789, dated January 6, 1903.

Application filed May 12, 1902. Serial No. 106,907. (No model.)

To all whom it may concern:

Be it known that I, HARRY SHOEMAKER, a citizen of the United States, residing at Philadelphia, in the county of Philadelphia and State of Pennsylvania, have invented a new and useful Wireless Signaling System, of which the following is a specification.

My invention relates to signaling between a plurality of stations by means of electroradiant energy impressed upon and transmitted through the natural media.

It relates particularly to the receiving apparatus, in which is used a wave-responsive device or devices controlling the recording apparatus indirectly through a transformer.

It consists, further, in means for completely shielding the wave-responsive device from the influence of nearby and powerful radiations comprising a metallic case, in which is located the wave-responsive device, a shielded connection through the walls of the casing, and a plate in contact with a connection forming a condenser with the walls of the casing.

It comprises, further, a wave-responsive device composed of iron and carbon and having the property of self-restoration.

For description of my invention reference is to be had to the accompanying drawings, in which—

Figure 1 is a diagrammatic view of the circuits at the receiving-station. Fig. 2 is a sectional view of a connection through a metallic case. Fig. 3 is a plan view of the metallic case, showing the connections through the walls thereof. Fig. 4 is an elevation of a shield for a connection extending through the walls of the casing. Fig. 5 is a cross-sectional view of Fig. 4. Fig. 6 is a view of the connection itself. Fig. 7 is an elevational view of the iron and carbon wave-responsive device. Fig. 8 is a section of Fig. 7. Fig. 9 is a side elevation of the receiving apparatus.

1 represents the usual aerial conductor at the receiving-station of a wireless signaling system, which connects in this instance through the parts 2, 2 of an inductance, which are joined through the condenser 3. The lower terminal of the inductance connects to earth-plate 4.

5 is a wave-responsive device comprising

carbon blocks *a*, in slight grooves of which rest the steel needles *b*. This device has the property of responding with great sensitivity to electrical radiations collected by the aerial conductor 1 and requires no restoring means after it has altered its condition due to received energy—that is, after having changed its resistance it immediately resumes its normal state upon the cessation of electrical waves.

7 is the primary coil of a transformer whose core is 8 and whose secondary is represented at 9.

6 represents a source of energy in series with the primary 7 and the wave-responsive device 5, there being normally a current from said source through the lower half of inductance 2, wave-responsive device 5, upper half of inductance 2, and primary coil 7. The condenser 3 prevents the short-circuiting of source 6 through the inductances 2, 2. This condenser 3, however, is chosen of such dimensions as not to interfere to any material amount with the electrical constants of the aerial conductor 1. Conductor 1, taken in conjunction with the inductance 2, 2, which in the preferred form of receiver form together a conductor syntonic with the transmitted waves, so that there is a great difference of potential exerted at the terminals of the wave-responsive device 5. Normally there is a current of certain magnitude flowing through the primary 7 and the device 5. Upon the reception of waves, however, and due to the rise of potential at the terminals of 5 the current through the primary 7 is changed, and during the period of such change there is induced in the secondary 9 a current which passes in series through the coils 10 of a relay and the electrolytic cell 11. The cell 11 comprises aluminium and carbon electrodes submerged in a solution of potassium hydroxid. The purpose of this cell is to prolong and smooth out the impulses induced in the secondary 9. It appears, therefore, that only during changes of current in the primary 7 or, in other words, only during changes in the condition of wave-responsive device 5 is the relay 10 actuated. The relay-tongue 12 when in contact with 13 closes the circuit 100

through source 14 and the recording device or other translating device 15. This arrangement permits using a much more sensitive relay than ordinarily and, furthermore, gains the advantage that normally there is no current whatever through the relay which there would be, however, in the case if the relay 10 were to replace the primary 7. With the type of wave-responsive device described this arrangement is particularly advantageous, for both with the carbon-iron combinations and the anticoherer combinations there is always a current flowing through the wave-responsive device. It is to be understood, however, that in place of the wave-responsive device 5 I may use the ordinary filings-coherer with its taper controlled by the relay 10, the advantage in this arrangement being that with the cell 11 used in conjunction with the transformer there is a smoothing out of the numerous impulses into something resembling very accurately the dots and dashes of a code, as in the case of ordinary telegraphy over metallic conductors.

16 is a wall of a metallic casing in which the wave-responsive devices are inclosed in order to protect them from powerful radiations when near at hand. Connections are made through said walls 16 by means of rods 23, screw-threaded at each end to receive binding-screws 24. 23 is insulated by a material 22 from the sleeves 21, which are secured in the walls 16 and also in a plate 20. Between plate 20 and wall 16 is a metallic sheet 18 in electrical connection with rod 23 and insulated by dielectric 17 and 19 from 16 and 20, respectively. It is seen, therefore, that rod 23 is in a condenser-like relation with respect to the walls of the receptacle. Any radiations, therefore, tending to run into the interior of the casing 16 along the conductors connecting with 23 on the outside of such casing will be entirely prevented from passing beyond plate 19, which from its relation to the walls 16 is similar to a plate insulated from earth and near to earth. The oscillations, therefore, stop at plate 19.

28 28 are also metallic connections extending through the walls 16 and having at their ends the disks 27. These rods 28 are housed in a metallic shell 25 and separated from said shell by the insulating-filling 29. Opposite the end 27 is an opening 26 in the shell 25. A flange 31, integral with the shell 25, abuts 55 against the walls 16, while the lower portion of shell 25, insulation 29, and rod 28 extend through a large opening in said wall 16. On the inside of said wall and threaded upon the shell 25 is the nut 30, which secures said shell 60 mechanically to the casing. On the inner end of rod 28 are the nuts 32 and 33, forming a binding-post. Mounted outside of said casing upon the base 38 of the instrument, upon which is secured at 39 the relay and at 40 the 65 battery-box, is a pair of electromagnets 41 on each side of the casing 16. These magnets when energized attract armature 42 in oppo-

sition to spring 43, which is adjustable by screw 44. At the upper end of armature 42 is secured the insulating-bracket 45, through which passes the screw 46, whose terminal extends, when it is desired to receive messages into the hole 26 in the shell 25, into contact with the disk 27, thus making connection from one screw 46 from the aerial conductor to the wave-responsive device and from the other terminal of said wave-responsive device to the other screw 46 to earth. Magnets 41 are energized when it is desired to transmit from a station, in which case armature 42 is attracted, resulting in a break of circuit between screws 46 and disks 27, thereby completely isolating the wave-responsive device within the metallic box 16 and preventing any waves from entering to the same in virtue of the metallic shell 25, which has a small opening 26 only and through which waves cannot pass.

In Fig. 7, 34 and 35 are blocks of carbon having slight concavities opposite each other in their inner faces, in which concavities rest the steel balls 36. The blocks 34 and 35 are secured to a suitable insulating-base by screws passing through the holes 37. In place of steel balls carbon balls may be used, in which case blocks 34 and 35 are steel. This device has the same properties as described in connection with wave-responsive device 5—namely, that of self-restoration. By employing a comparatively large number of 100 balls, as shown in Figs. 7 and 8, the device is more certain in its action and permits, if desired, a quite large current to normally circulate through it.

I do not wish to be understood as limiting myself to the precise arrangement of parts and devices hereinbefore described, inasmuch as many variations may be made by any one skilled in the art and still not depart from my invention.

What I claim is—

1. In a signaling system, a self-restoring wave-responsive device, a source of energy in circuit with said device and the primary of a transformer, and a recording device controlled by the secondary of said transformer.
2. A wave-excluding means comprising a metallic wall, a connection through said wall and insulated therefrom, and an extension of said connection in condenser relation with said wall.
3. A wave-excluding means comprising a metallic wall, a connection through said wall and insulated therefrom, a metal jacket outside said wall inclosing said connection, and a perforation in said jacket.
4. In a signaling system, a wave-responsive device, a source of energy in circuit with said device and the primary of a transformer, a translating device controlled by the secondary of said transformer, and means for prolonging the currents in the secondary circuit.
5. In a signaling system, a receiving-conductor, an inductance in series therewith, a

wave-responsive device in shunt to said inductance, a source of energy and the primary of the transformer in a circuit with said wave-responsive device, and signal-producing means actuated by the currents derived from the secondary of said transformer.

6. In a signaling system, a wave-responsive device, a circuit including said device, a source of energy and the primary of a transformer,

signal-producing means in the secondary circuit of said transformer, and an electrolytic cell in said secondary circuit operating to prolong the impulses in the secondary circuit.

HARRY SHOEMAKER.
